SAFETY FOR FIREARMS

Le Roy B. Fraser, Woodbridge, Conn.

Application July 9, 1945, Serial No. 603,891

5 Claims. (Cl. 42—70)

1

This invention relates to guns and, while it is particularly designed for application to guns for beginners in the use of firearms, it is not necessarily limited in this respect. It also, in some respects, is particularly designed for use with short guns or pistols, but may be applied and used to advantage with shoulder guns as well.

The use of hand guns or pistols is sometimes considered more dangerous than that of long or shoulder guns, and, for this reason, safety devices have, in many instances, been applied to such firearms. While various safety appliances have been provided, such appliances usually are not foolproof in that, while they may, in many instances, prevent accidental discharge of the gun, it is still possible for it to be accidentally discharged with unfortunate results.

I contemplate by the present invention the provision of a gun which will be so constructed so that it cannot be fired without the deliberate intent of the user. In the embodiment of my invention shown in the accompanying drawings, this is effected by surrounding the trigger of the firearm with a movable guard, the guard normally standing in such a position that the trigger will be effectively shielded from contact or engagement with any object. Locking or detent means are provided to hold the trigger guard in operative position, which means will be in turn controlled or moved to inoperative position by proper gripping or handling of the gun when its discharge is intended. In addition to shielding the trigger, the guard also prevents actuation of the trigger until moved to its inoperative position.

As illustrated, the trigger guard is normally urged to its operative position by a spring and, after being freed for movement, is raised or moved to expose the trigger by the trigger finger of the user. This produces a steadyng effect of the finger on the trigger, so that a more steady squeezing action of the finger on the trigger is obtained, and thus the technique of the shooting of the gun is improved. Thus the advantage arising from the use of the invention lies not only in the safety feature, but also in the fact that it trains a beginner in the proper technique of firing the gun.

One object of the present invention is to provide a new and improved safety feature for guns.

A still further object of the invention is to provide a gun which may not be fired without the deliberate intent of the user.

Still another object of the invention is to pro-

2

vide a firearm which will be useful in teaching to beginners the proper handling of a gun in shooting.

To these and other ends the invention consists in the novel features and combinations of parts to be hereinafter described and claimed.

In the accompanying drawings:

Fig. 1 is a side elevational view of a hand gun or pistol embodying my improvements;

Fig. 2 is an enlarged view of the portion of the gun adjacent the trigger;

Fig. 3 is a view similar to Fig. 2 showing the trigger guard and retaining or detent member in a different position;

Fig. 4 is a partial side elevational view of a shoulder gun or rifle equipped with my invention;

Fig. 5 is a fragmentary view, partly in section, of the gun shown in Fig. 4, showing the parts in another position;

Fig. 6 is a side elevational view of a shoulder gun having a trigger guard embodying my invention, which guard is controlled in a different manner;

Fig. 7 is a view, partly in section, of the gun shown in Fig. 6;

Fig. 8 is a sectional view on line 8—8 of Fig. 7; and

Fig. 9 is a sectional view on line 9—9 of Fig. 7.

To illustrate one embodiment of my invention, I have shown in Fig. 1 of the drawings a pistol or hand gun comprising a frame portion 10, a barrel 11, and a grip 12. Pivoted in the frame portion of the gun and projecting therefrom is a trigger 13 provided with a guard designated generally by the numeral 14, the guard being secured to the frame at its forward end by a screw 15 or some similar retaining member. The guard 14 is of channel or U-shaped form in cross section and extends rearwardly to receive be-

tween its side walls the outer portion of the trigger 13. The member 14 may also be provided with a bottom wall 16 which is provided with an opening 17 through which the lower portion of the trigger may project when the guard is raised

as shown, for example, in Fig. 3. The bottom wall 16 of the guard may be extended forwardly as shown at 16a to provide a resilient or spring

end portion to receive the screw 15, so that the guard is movable about the tongue portion 16a.

The resilience of this portion will, however, normally maintain the guard in its operative or shielding position as shown in Fig. 2.

The guard is also provided with a rear wall 18 which normally stands closely adjacent the rear face of the lower end of the trigger as shown

in Fig. 1. The guard 14 is held in its operative position by a detent member 19 which is

normally urged into a notch 20 in the rear wall 18 by a spring 21. The guard 14 is held in its inoperative position by a detent member 22 which is

normally urged into a notch 23 in the rear wall 18 by a spring 24. The guard 14 is held in its inoperative position by a detent member 25 which is

in Fig. 2, so that it will positively prevent the trigger being pulled rearwardly. Thus the guard not only shields the trigger and prevents the engagement of the finger or other object with the trigger, but also by the engagement of the rear wall back of the trigger prevents movement of the latter. If necessary, the upper portion of the trigger may be cut away or recessed slightly as shown at 19 so that it may have sufficient movement or travel to fire the gun when the guard is in its raised or inoperative position as shown in Fig. 3.

While the trigger guard is normally held in the position shown in Fig. 2 by the inherent resiliency of the portion 16^a, means are provided for locking or retaining the guard in this position except when the gun is intended to be fired. A retaining or retaining member is pivoted to the grip portion of the gun at 20, this member having a nose portion 21 designed to engage above a shoulder or projection 22 on the trigger guard; so as to prevent upward movement of the latter. The retaining member is also provided with a body portion 23 which extends downwardly along the forward face of the grip 12, and a spring 24 mounted in the grip bears against the body portion 23 to normally hold the latter forwardly and hold the nose portion in engagement with the trigger guard. The grip portion of the gun is provided with a recess 25 to receive the portion 23 of the retaining member when the fingers of the user grip the gun and squeeze the part 23 toward the grip. This position of the parts is shown in Fig. 3 where it will be noted the retaining member has been moved downwardly and rearwardly so it no longer engages the shoulder 22 on the trigger guard.

The normal position of the parts is shown in Fig. 2 where, as will be apparent, the guard embraces the trigger and prevents engagement of any object therewith and also prevents the rearward movement of the trigger, the guard being retained in this position by the detent 21 of the retaining member. When the user desires to fire the gun, and grasps the grip 12 in his hand in position for firing, his fingers will extend around the forward portion of the grip and squeeze the body portion 23 of the retaining member into the recess 25, thus releasing the nose 21 from the shoulder 22. The trigger finger of the user is then drawn rearwardly and upwardly along the lower wall 16 of the guard, thus moving the guard upwardly against the tension of the spring portion 16^a from the position shown in Fig. 2 to that shown in Fig. 3. The pressure of the guard on the finger will bring about a steady action, so that, as the finger is drawn rearwardly along the lower surface of the guard, it will contact the trigger by a steady squeezing movement and result in more accurate marksmanship. Thus, while the improved trigger guard is useful as a safety device, it will also improve the technique of the user of the gun.

In Figs. 4 and 5 of the drawings, I have shown my invention as applied to a shoulder firearm. In this case, the guard 14^a, which is constructed in a manner generally similar to the guard 14, is pivoted to the forearm of the gun at 30. The rear portion of the forearm may be provided with a recess 31 to receive the guard when it is raised to expose the trigger 32 as shown in Fig. 5. In this case, it will be noted that the guard is relatively wide or deep and covers substantially the entire trigger, a construction which is possible when the frame or forearm of the gun may be

recessed as at 31 to receive the guard. A spring 33 normally urges the guard downwardly to its operative position, the spring acting against laterally turned lugs 34 at the upper edges of the side walls of the guard. A retaining or detent member 35 is pivoted at 36 adjacent the grip of the gun, this member engaging a shoulder 37 on the guard as described in connection with the form of my invention illustrated in Figs. 1 to 3. The retaining member 35 is normally held in its operative position by the spring 38 acting against the tail portion 39 which is adapted to be received in a recess 40 in the grip of the gun when it is grasped by the user in the normal way in which a gun would be held when it is to be fired.

The operation of the modification of my device shown in Figs. 4 and 5 is similar to that shown in Figs. 1 to 3, and detailed description of the operation, therefore, will not be necessary. When the guard is unlocked by the gripping of the gun in the normal way, it may be raised by the trigger finger of the user being drawn rearwardly with slight upward pressure along the lower portion of the guard; thus raising the latter member from the position shown in Fig. 4 to that shown in Fig. 5 in which position the trigger finger may engage and squeeze the trigger rearwardly to discharge the gun.

In Figs. 6 to 9 of the drawings, I have shown a shoulder firearm equipped with a trigger guard embodying my invention, the guard; however, being controlled in a different manner. In my previous Patent No. 2,122,415, granted July 5, 1938, I have illustrated a gun so constructed that it may not be discharged until the required shoulder and cheek pressures are exerted upon it by the user. In other words, if a shoulder gun is held properly, it will be pressed firmly against the shoulder of the user, and also the cheek of the user will be pressed against the side of the stock. The principle, developed in the patent referred to, of preventing the discharge of the firearm until it is properly held and grasped by the user is, in this modification of the present invention, applied to the movable trigger guard, so that the latter is not released until the proper shoulder and cheek pressures have been exerted.

As shown in Figs. 6 to 9 of the drawings, the stock 45 of the gun is provided with a reduced rear portion or post 46, and slidably telescoped over this post is a supplemental stock or sleeve portion 47 held in place by the butt 48 secured to post 46. Upon the rear end of the post 46 is secured a plate 49 in which is threadedly mounted a screw 50 passing loosely through an opening 51 in the butt 48, the head of the screw being disposed in a recess 52. A spring 53 is mounted upon the screw between the plate 49 and the butt 48, thus normally holding the latter in a rearward or extended position. Pressure, however, of the butt 48 against the shoulder will move the butt 48 forwardly in opposition to the pressure of the spring, and, as the butt rests against the rear end of the portion 47, this will also move the latter forwardly with respect to the post. The butt 48 may be guided in its movement by dowel pins 54 secured to the butt and slidably mounted in openings 55 in the post.

As shown in Fig. 9, the opening 56 in the supplemental stock portion 47 is somewhat larger than the post 46, especially at the upper edge of the latter, so that the member 47 may be rotated or pivotally moved to a slight extent with respect to the post. A pivot pin 57 is secured to the plate 49 at one end and at its other end

is supported by the butt 48. A bracket 58 is loosely mounted on this pivot pin and secured to the stock member 47, a compression spring 59 acting between the plate 49 and the bracket 58. This spring tends to hold the member 47 in a rearward position against the butt 48 and also serves as one of two pivotal mountings for the stock portion 47. The other pivotal mounting is constituted by the rod 60 secured to the stock portion 47 and rotatably mounted at its forward end at 61 in the stock 45. A spring 62 surrounds this rod and normally urges the stock member 47 rearwardly toward the butt. Pressure of the cheek against the member 47 may swing the stock in a clockwise direction as shown in Fig. 9 to its dotted line position about the pivot pins 57 and 60. This, however, does not move the butt 48 as the latter is secured to the post 46 and not to the member 47.

Pivoted at 63 to the post 46 is a lever 64, the lever being normally held in the position shown in Fig. 8 by a compression spring 65. Adjacent the rear end of this lever is a lug 67 normally spaced slightly forwardly of a lug 68 on the movable stock portion 47. In the normal position of the parts, the lug 68 does not engage the lug 67. However, when the gun is pressed against the shoulder, and the butt 48 and sleeve member 47 are moved forwardly, the lug 68 will be moved forwardly and will be in position to engage the lug 67 when the sleeve portion 64 is given a rotating movement by cheek pressure. Therefore, by a combination of shoulder pressure and cheek pressure, the lever 64 will be moved in a counterclockwise direction as shown in Fig. 8.

The lever 64 extends forwardly through the grip portion of the gun and is provided with a laterally turned portion 69 at its forward end designed to overlie the horizontal portion of an L-shaped lug 70 at the rear end of a trigger guard 71 pivoted at 72 to the forearm of the gun and normally held in a downward position by the spring 73 acting against inturned lugs 74. It will be understood that this trigger guard and its operation are similar to the construction and operation of the trigger guard shown in Figs. 4 and 5.

In the normal position of the parts, the forward end 69 of the lever 64 holds the trigger guard downwardly in the position in Fig. 7, which not only prevents engagement of the trigger by the finger of the user, but also, by engagement of the rear wall 75 with the trigger 76, blocks the trigger against movement. When, however, the gun is pressed against the shoulder, thus moving the sleeve portion 47 forwardly and is also engaged by the cheek with sufficient pressure to rotate the portion 47 about the pivot pins 57 and 60, the lug 68 will be caused to engage lug 70 and swing the lever 64 in a counterclockwise direction as shown in Fig. 8, to as to remove the end 69 of this lever from engagement with the portion 70 of the trigger guard, and thus permit the latter to be moved upwardly by pressure of the trigger finger of the user thereagainst. Therefore, the trigger guard is in locked position until the proper shoulder and cheek pressures are applied to the gun. When the cheek and shoulder pressures are released, the portion 47 will be moved pivotally to its normal position by the spring 65 and will be moved rearwardly against the butt 48 by the springs 59 and 62, the butt, of course, being returned by the spring 53.

While I have shown and described some pre-

ferred embodiments of my invention, it will be understood that it is not to be limited to all of the details shown, but is capable of modification and variation within the spirit of the invention and within the scope of the claims.

What I claim is:

1. In a firearm, a frame, a trigger pivoted thereto, a guard member for the trigger adapted to normally embrace the latter, means movably connecting said guard member to the frame to swing toward and from the frame about an axis transverse to the plane of movement of the trigger, means normally urging said member away from the frame to a position in which it shields the trigger against engagement by the finger, said member when in said position preventing operation of the trigger, and retaining means to prevent movement of said member toward the frame and away from shielding position.

2. In a firearm, a frame, a trigger pivoted thereto, a guard member for the trigger adapted to normally embrace the latter, means movably connecting said guard member to the frame to swing toward and from the frame about an axis transverse to the plane of movement of the trigger, means normally urging said member away from the frame to a position in which it shields the trigger against engagement by the finger, said member when in said position preventing operation of the trigger, and retaining means to prevent movement of said member toward the frame and away from shielding position, said retaining means being controlled by the gripping of the firearm by the user.

3. A firearm comprising a frame, a grip, a trigger pivoted to the frame and extending below the same, a guard member hinged to the frame forwardly of the trigger to move about an axis transversely to the plane of movement of the trigger and formed to embrace the latter and shield it against engagement by the finger of the user, and spring means normally urging said member downwardly away from the frame to shielding position, said member having a part disposed rearwardly of the trigger to prevent movement of the latter.

4. A firearm comprising a frame, a grip, a trigger pivoted to the frame and extending below the same, a guard member hinged to the frame forwardly of the trigger to move about an axis transversely to the plane of movement of the trigger and formed to embrace the latter and shield it against engagement by the finger of the user, spring means normally urging said member downwardly away from the frame to shielding position, said member having a part disposed rearwardly of the trigger to prevent movement of the latter, a detent member normally engaging said part, and means movably mounting said detent member to permit it to be moved to disengaging position.

5. A firearm comprising a frame, a grip, a trigger pivoted to the frame and extending below the same, a guard member hinged to the frame forwardly of the trigger to move about an axis transversely to the plane of movement of the trigger and formed to embrace the latter and shield it against engagement by the finger of the user, spring means normally urging said member downwardly away from the frame to shielding position, said member having a part disposed rearwardly of the trigger to prevent movement of the latter, a detent member normally engaging said part, means movably mounting said detent member to permit it to be moved to disengaging

position, and said detent member having a part disposed adjacent the grip of the firearm to be controlled by a finger of the user.
